(57) **CLAIM**

The ornamental design for a wearable article, as shown and described.

DESCRIPTION

FIG. 1 is a perspective view of a wearable article, showing my new design;

FIG. 2 is an enlarged perspective view thereof, indicated by line 2-2 in FIG. 1.

FIG. 3 is an enlarged front elevation view thereof, taken along line 3-3 in FIG. 6.

FIG. 4 is an enlarged rear elevation view thereof, taken along line 4-4 in FIG. 6.

FIG. 5 is an enlarged left elevation view thereof, taken along line 5-5 in FIG. 6, the right elevation being a mirror image thereof.

FIG. 6 is an enlarged top plan view thereof.

FIG. 7 is an enlarged bottom plan view thereof; and,

FIG. 8 is a top plan view thereof, shown in a used condition. The broken lines shown in the drawings depict portions of the wearable article that form no part of the claimed design. The dot-dash broken lines depict boundary lines and form no part of the claimed design.

1 Claim, 6 Drawing Sheets
